SPRING LOCK PANEL RECEPTACLE

Harvey Hubbell, Long Hill, and Joseph F. Healy, Jr., Bridgeport, Conn., assignors to Harvey Hubbell, Incorporated, Bridgeport, Conn., a corporation of Connecticut

Application October 7, 1943, Serial No. 505,318

7 Claims. (Cl. 173—363)

1

This invention relates to a panel receptacle or connection adapted to be mounted on a panel and to receive a pin or plug connected to a conductor or lead wire for connecting it to and disconnecting it from a conductor permanently connected with the receptacle, and has for an object to provide such a receptacle which will be simple and effective in construction and in which the pin connected with the conductor may be quickly inserted and removed, but which after being inserted in the receptacle is substantially locked therein so that it will not be withdrawn inadvertently or by considerable strain on the conductor, although it is preferred that the construction be so designed that the connection will yield or separate before there is sufficient strain to break or injure the conductor or the receptacle.

With the foregoing and other objects in view we have devised the construction illustrated in the accompanying drawing forming a part of this specification. It is, however, to be understood the device is not limited to the specific construction and arrangement shown but may include various changes and modifications within the scope of the invention.

In this drawing:

Fig. 1 is a longitudinal section through the receptacle mounted in position in the panel showing the pin on the end of the conductor to be connected thereto about to be inserted in the receptacle;

Fig. 2 is a similar section showing the pin inserted in position in the receptacle;

Fig. 3 is a side elevation of the contact and gripping means within the receptacle;

Fig. 4 is a transverse section substantially on the line 4—4 of Fig. 3 on an enlarged scale;

Fig. 5 is a similar section showing the conductor pin inserted;

Fig. 6 is a side elevation of the insulating sleeve or body for enclosing the receptacle contact;

Fig. 7 is an end view thereof, and

Fig. 8 is a transverse section substantially on the line 8—8 of Fig. 6.

The receptacle is shown as mounted in a panel 10 of insulating or other material, this panel being provided with a transverse opening or passage 11 therethrough in which the receptacle is mounted. This receptacle comprises a body or sleeve 12 of insulating material extending through the opening or passage 11 and provided with an enlarged head 13 engaging one side of the panel. The body portion is threaded as indicated at 14 to receive a nut 15 connected to

2

this body at the opposite side of the panel to clamp the receptacle in position in the panel. To facilitate assembly the sleeve or body 12 is split longitudinally as indicated at 16 so that it is divided into two separable sections and on its interior is provided with a chamber 17 preferably noncircular in cross section, as indicated in Fig. 8, so that it has flat sides 18. This chamber is closed at its opposite ends by end wall 19 provided with an opening 21 for passage of the conductor 22 and a wall 23 provided with an opening 24 for passage of a plug-in pin 25 on a conductor 26 connected with any suitable electrical device desired to be connected with the receptacle.

15 The conductor 22 may have connected to it a lead 27 connected to any source of current or electrical device or wiring system as desired. At its inner end the conductor 22 is reduced somewhat as shown at 28 and extends through an opening in the end wall 29 of a longitudinally split metal sleeve 30. This is a spring sleeve preferably made of spring brass or bronze and is provided on its opposite sides with substantially wide slots 31, and at the opposite end from the lead 22 is reduced in diameter to provide flanges 32 to engage and grip the pin 25 when it is inserted in the receptacle to make good electrical contact therewith. This sleeve 30 encloses a coil spring 33 embracing the reduced portion 28 of the conductor 22 tightly gripping the same, and both this end portion of the spring 33 and the inturned end 29 of the sleeve 30 are soldered to the conductor 22, as indicated at 34 and 35, so as to permanently connect them to the conductor and also provide a good electrical connection.

30 The spring 33 is preferably of good electrical conducting material, such for example as bronze spring wire and is so wound that its internal diameter is somewhat less than the external diameter of the pin 25 so that when the pin 25 is inserted in the spring the spring is expanded somewhat by the pin and tends to contract to firmly grip the pin. To limit turning movements of the free end of the spring within the sleeve 45 30 its free end is turned outwardly as indicated at 36 to extend into one of the longitudinal slots 31 in the side of the sleeve 30. If greater movement of the turned-out end 36 is desired than is permitted by the width of the slot 31, the opposite side edges of the slot may be provided with notches 37 and 38 adjacent the free end of the sleeve to thus permit greater movement of the outturned end 36.

55 The spring 33 may be wound either right or left hand but it is preferably wound left handed

as shown. When inserting the pin 25 if it is turned to the right or clockwise as it is pushed into the spring it will tend to unwind the coils of the spring 33, thus somewhat enlarging or expanding the spring so as to permit the pin 25 to slide longitudinally into the spring to the position shown in Fig. 2. As the pin is released by the operator and the turning action ceases the spring will tend to contract and firmly grip the pin, and if a strain is placed on the lead or conductor 26 or the pin 25 tending to draw it straight out from the receptacle this will tend to stretch or elongate the spring longitudinally and this will tend to further contract the spring to a smaller diameter so that it will grip the pin 25 more firmly. Therefore the greater the strain on the pin 25 the greater will be the gripping effect on the pin, of course up to a certain limit where the strain would be sufficient to withdraw the pin. It is preferred that the device be so designed that the pin will be released before the strain is sufficient to break the lead or conductor 26 or break the elements of the receptacle, but it will be seen that with this construction the pin 25 is normally substantially locked in the receptacle against inadvertent withdrawal therefrom and against withdrawal by ordinary strain upon the lead 26. The reduced free end wall of the sleeve 30 leading to the flanges 32 will limit the elongated or stretching movement of the spring so that it cannot be stretched sufficiently to collapse it, and the notches 37 and 38 will permit sufficient peripheral movement of the out-turned end 36 to allow sufficient radial expansion of the spring for insertion and removal of the pin 25, but will prevent turning of the spring sufficiently to cause its collapse or set from normal size and position.

The entrance opening in the free end of sleeve 30 between flanges 32 is somewhat smaller than the external diameter of pin 25 so that when the pin 25 is inserted through the open end of the sleeve 30 as it passes to the spring it will expand somewhat the reduced end of the sleeve 30 thus separating somewhat the flanges 32 and the spring action of the sleeve 30 will cause these flanges to grip the pin 25 and make good electrical contact therewith. Therefore with this arrangement the entire current is not carried by the spring 33 between the inner end of the pin 25 and the conductor 22, but the sleeve 30 also provides an auxiliary or supplemental conducting means from the pin 25 to the conductor 22, obviating the possibility that the spring might be injured by overheating and also providing better electrical capacity and conductivity through the receptacle. The noncircular cross-sectional shape of the chamber 17 within the body or sleeve 12 conforms generally to the shape of the sleeve 30 so that this sleeve is held against turning movements within the body 12 due to turning movements of the pin 25, the side edges of the slots 31 engaging the flat walls 18 to prevent turning of the sleeve. The pin 25 may be readily withdrawn from the receptacle when desired by merely turning it in the same direction or that is clockwise with a left-hand wound spring, and pulling outwardly at the same time on the pin. Turning the pin to the right or contrary to the direction the spring is wound tends to expand the spring radially the same as when inserting the pin, and as the spring expands it releases the pin so that it may be readily withdrawn from the spring and from the receptacle. If the spring were wound in the opposite direction or right-hand, then the

pin 25 would be turned to the left or counterclockwise as it is inserted into or withdrawn from the spring to secure the enlarging or releasing action of the spring. As the body or sleeve 12 is made of two sections the assembled sleeve 30, spring 33 and conductor 22, as shown in Fig. 3, may be inserted in the portion of the chamber 17 in one-half of the body and then the other half placed in position to entirely enclose the sleeve 30, and then this assembly can be inserted in the opening 11 in the panel and the nut 15 applied to clamp it in position.

It will be seen from the above the device is of very simple construction and may be easily and quickly mounted in any panel or similar device having an opening or passage therethrough of the desired size, and it will be firmly mounted in position; also that the pin 25 may be easily and quickly inserted into or removed from the receptacle to connect the conductor 26 to the conductor 22 or disconnect it therefrom, and that when the pin 25 is in position it is substantially locked against accidental withdrawal. The spring is not necessarily of round wire as shown, but it could be made of a flat or other desired form of wire.

Having thus set forth the nature of our invention, what we claim is:

1. A receptacle of the character described comprising a body of insulating material adapted to be mounted in a panel or similar support and provided with a longitudinally extending chamber noncircular in cross section, a substantially cylindrical coiled spring in the chamber, a spring metal sleeve enclosing the spring and of a cross section to cooperate with the walls of the chamber to be held against turning therein, a conductor extending through the body into the chamber and connected to one end of the sleeve and of the spring, said body being provided with an opening in alignment with the other end of the sleeve and the spring for insertion of a substantially cylindrical conductor pin into the sleeve and spring, the spring being adapted to be expanded by a pin of somewhat greater external diameter than the internal diameter of the spring when such a pin is inserted therein so as to grip the pin.
2. A receptacle of the character described comprising a sleeve of insulating material adapted to be mounted in an opening in a panel or similar support, said sleeve being provided with a longitudinal chamber having opposite flattened sides, a substantially cylindrical coiled spring in said chamber, a spring metal sleeve enclosing the spring provided with relatively wide longitudinal slots in opposite sides whose edges cooperate with the flattened sides of the chamber to prevent turning movements of this latter sleeve therein, a conductor extending through one end of the first sleeve and connected to the metal sleeve and the spring, the other end of the first sleeve having an opening in alignment with the free ends of the metal sleeve and the spring for insertion of a substantially cylindrical conductor pin, and the spring and the free end of the metal sleeve being adapted to be expanded by a pin of somewhat greater external diameter than the internal diameter of the spring when such a pin is inserted therein so as to grip the pin.
3. A receptacle of the character described comprising a sleeve of insulating material adapted to be mounted in an opening in a panel or similar support and split longitudinally into two parts,

said sleeve being provided with a longitudinal chamber closed at its opposite ends by walls each having an opening therein, a substantially cylindrical coiled spring in the chamber in alignment with said openings, a longitudinally slit spring sleeve enclosing the spring and of greater diameter than the openings in the first sleeve, a conductor extending through one of said openings and connected to one end of each of the second sleeves and this spring, said other opening being adapted for insertion of a substantially cylindrical conductor pin into the free ends of the metal sleeve and the spring, and said spring and free end of the metal sleeve being adapted to be expanded by a pin of somewhat greater external diameter than the internal diameter of the spring when such a pin is inserted therein so as to grip the pin.

4. A receptacle of the character described comprising an insulating body member adapted to be mounted in an opening in a panel or similar support and provided with a longitudinal chamber, a substantially cylindrical coiled spring in said chamber, a spring metal sleeve enclosing the spring and provided with a substantially wide longitudinal slot in one side, a conductor extending into the chamber and connected to one end of the metal sleeve and the spring, the free end of the spring being turned outwardly so as to extend into said slot and engage the opposite sides thereof to limit turning movements of the free end of the spring, said body having an opening in alignment with the free end of the spring for insertion of a conductor pin into the spring, and said spring being adapted to be expanded by a pin of somewhat greater external diameter than the internal diameter of the spring when such a pin is inserted therein so as to grip the pin.

5. A receptacle of the character described comprising an insulating body member adapted to be mounted in a panel or similar support and provided with an internal chamber, a substantially cylindrical coiled spring in said chamber, a spring metal sleeve enclosing the spring, a conductor connected to the spring and the sleeve at one end, said body being provided with an opening in alignment with the free end of the spring leading to said chamber for insertion of a substantially cylindrical pin connected to another conductor, the spring being adapted to be expanded by a pin of somewhat greater external diameter than the internal diameter of the spring when such a pin is inserted therein so as to grip the pin, and means on the free end of the sleeve to grip the pin to provide electrical connection therewith.

6. A receptacle of the character described comprising a sleeve of insulating material adapted to

be mounted in an opening in a panel or similar support, said sleeve being provided with a head at one end to engage one side of the panel and being threaded at the other end for a nut to clamp it in the panel, said sleeve being provided with a longitudinal chamber, a substantially cylindrical coiled spring in said chamber, a longitudinally split spring metal sleeve enclosing the spring, a conductor passing through one end of the first sleeve and connected to the metal sleeve and the spring, said first sleeve being provided with an opening in its other end leading to said chamber in alignment with the end of the spring for insertion of a substantially cylindrical pin connected to another conductor, said spring being adapted to be expanded by a pin of somewhat greater external diameter than the internal diameter of the spring when such a pin is inserted therein so as to grip the pin, and said spring sleeve being provided with inturned flanges at its free end to grip the pin.

7. A receptacle of the character described comprising a sleeve of insulating material adapted to be mounted in an opening in a panel or similar support, said sleeve being provided with a longitudinal chamber, a substantially cylindrical coiled spring in said chamber, a metal sleeve enclosing the spring, a conductor extending through one end of the first sleeve and connected to the metal sleeve and the spring, said first sleeve having an opening in its other end in alignment with the spring for insertion of a conductor pin into the spring, said spring being adapted to be expanded by a pin of somewhat greater external diameter than the internal diameter of the spring when such a pin is inserted therein so as to grip the pin, the free end of the spring being turned outwardly, and means on the metal sleeve cooperating with said free end of the spring to limit turning movements of the free end of the spring in the sleeve.
